UNITED STATES PATENT OFFICE

2,223,278

MOTOR STARTER

Fred H. Winter, Schenectady, N. Y., assignor to
General Electric Company, a corporation of
New York

Application December 14, 1939, Serial No. 309,219

6 Claims. (Cl. 172—288)

This invention relates to motor starters, more particularly to multi-point motor starters, and it has for an object the provision of a simple, reliable, improved, and inexpensive motor starter of this character.

In carrying the invention into effect in one form thereof, a current limiting device such as a resistor is connected in the armature circuit of the motor and switching means are provided for sequentially rendering portions of this current limiting device ineffective. This switching device comprises a plurality of magnetic circuits which are spaced apart so as to be magnetically independent of each other together with a single operating coil interlinking all of these magnetic circuits. The magnetic circuits are separately adjustable to respond to different values of magnetic flux for actuating contacts which control portions of the current limiting device. A suitable energy storage device is provided which discharges a decaying current through the coil thereby causing the independent magnetic circuits to respond sequentially to the different values of flux to which they are adjusted to render portions of the current limiting device ineffective.

For a better and more complete understanding of the invention, reference should now be had to the following specification and to the accompanying drawing, in which Fig. 1 is a simple, diagrammatical sketch of an embodiment of the invention and Fig. 2 is a modification.

Referring now to the drawing, the armature 10a of a motor 10 is arranged to be connected to a suitable supply source which is represented by the conductors 11, 12. Motor 10 is provided with a separately excited field winding 10b which is arranged to be connected by means of switch 13 to supply source 11, 12 or to any other suitable source of excitation.

40 A suitable current limiting device such as a resistor 14 is connected in circuit with the armature 10a of motor 10, and a suitable electromagnetic switching device 15 is provided for sequentially rendering portions 14a, 14b, and 14c of the current limiting device ineffective.

Switching device 15 comprises a plurality of separate magnetic circuits illustrated as the core structures 16, 17, and 18 of a plurality of normally closed contactors. These core structures are separated from each other so that they are substantially magnetically independent of each other, i. e., so that the flux of one core structure does not pass into another core structure. For the purpose of reducing magnetic leakage between the 55 separate magnetic circuits to a minimum, spacers

(not shown) made of a nonmagnetic material such as brass are placed between the core structures. The spacing of the core structures illustrated in the drawing is exaggerated for the purpose of clear illustration of the electrical circuits. 5 Core structures 16, 17, and 18 are respectively provided with armatures 16a, 17a, and 18a and with normally closed contacts, 16b, 17b, and 18b, respectively, which are opened in response to attraction of the armatures. These contacts control the short circuiting and insertion in the armature circuit of portions 14a, 14b, and 14c of current limiting device 14. The core structures are provided with adjusting screws 16c, 17c, and 18c, respectively, for adjusting the pressure of 15 the movable contacts against the stationary contacts. Adjustment of these adjusting screws naturally affects the time of pick up and drop out of the armatures. If it is desired to have the same pressure on all contacts and also to cause 20 the armatures to respond at different values of flux to provide sequential operation, additional means such as shims for varying the reluctances of the magnetic circuits are provided. Such shims may be secured to the faces of the armature opposite the core face at the movable end of the armature. Thus by means of the adjusting screws or by means of a combination of adjusting screws and shims, the value of flux at which the armatures respond and the time of response can be 25 varied as desired.

A single operating coil 19 is provided for exciting the separate core structures. As shown in the drawing, this coil links all of the core structures.

35 A suitable electrical energy storage device such as the condenser 20 is provided for discharging a decaying current through the coil 19 so that the armatures 16a, 17a, and 18a which are adjusted for response to different values of magnetic flux 40 will operate in sequence.

For the purpose of initiating operation of the starter, a suitable control device illustrated as a manually actuated push button type switch 21 is provided. An electromagnetically actuated contactor 22 which is responsive to actuation of starting control device 21 is provided for connecting the armature of the motor to its source of supply and for causing the condenser 20 to discharge through the operating coil 19.

50 With the foregoing understanding of the elements and their organization in the completed motor starter, the operation of the starter will readily be understood from the following detailed description.

55

It is assumed that the armatures 16_a, 17_a, and 18_a are adjusted to drop out sequentially in the order enumerated in response to the decaying current discharged into the coil 19 by condenser 20. It is also assumed that the parts are in the normal deenergized position in which they are illustrated in the drawing.

The field of the motor 10 is energized by closing switch 13 to connect field winding 10_b to the supply source 11, 12. The push button switch 21 is then depressed to close its contacts and connect operating coil 19 to the supply source 11, 12. The circuit is traced from the side 11 through "stop" push button 23, contacts of start push button 21, conductor 24, normally closed contacts 22_b of contactor 22, conductor 25, operating coil 19 to the side 12 of the supply source. Simultaneously, the push button 21 connects condenser 20 to the supply source through conductor 24, 20 normally closed interlock contacts 26 of the starting device and conductor 27 to side 12 of the supply source. The resistor 28 which controls the rate of discharge of the condenser is short circuited by the interlock contacts 26, and consequently the condenser 20 is connected directly across the supply source and charges at a rapid rate.

In response to the energization of operating coil 19, armatures 16_a, 17_a, and 18_a pick up and 30 separate their contacts 16_b, 17_b, and 18_b, thereby inserting portions 14_a, 14_b, and 14_c of resistor 14 in the armature circuit of motor 10. In picking up, armatures 16_a, 17_a, and 18_a close normally open interlock contacts 29_a and 29_b to complete 35 an energizing circuit for the operating coil of contactor 22 from the start push button 21 to the side 12 of the supply source. Interlock contacts 26 are also separated to insert resistor 28 in circuit with condenser 20. The movable contact 40 member 29_c of the interlock rests on push rods 16_d, 17_d, and 18_d which project from the movable contact members which are attached to armatures 16_a, 17_a, and 18_a. Thus all of the armatures 45 must be picked up and contacts 16_b, 17_b, and 18_b open with resistor sections 14_a, 14_b, and 14_c inserted in the motor circuit before contactor 22 can be energized to close to connect the motor armature to the source.

Contactor 22 picks up in response to energization and closes its normally open contacts 22_a and 22_b and opens its normally closed contacts 22_c. Contacts 22_b in closing complete the armature circuit of motor 10 to the supply source with resistor portions 14_a, 14_b, and 14_c included in circuit. As 55 a result motor 10 starts and accelerates. Contacts 22_b in opening interrupt the connections of coil 19 and condenser 20 to the supply source.

Contacts 22_a in closing complete a holding circuit for the coil of contactor 22 independent of 60 start push button 21 and the normally open interlocks 29_a, 29_b of the switching device 15. The push button 21 may now be released.

As soon as the connections of coil 19 and condenser 20 to the supply source are interrupted, 65 the condenser begins to discharge through the coil 19. Initially the discharge current is high but it decays at a rate determined by the resistance of the discharge resistor 28.

After a predetermined interval of time, the current will decay to the value at which armature 16_a is adjusted to drop out. As a result contacts 16_b close and short circuit portion 14_a of the resistor 14, and the speed of the motor is increased to a new value. After another predetermined interval 70 of time the discharge current of the condenser 20

will decay to a lower value at which armature 17_a is set to drop out. As a result contacts 17_b will close and short circuit portion 14_b of resistor 14, and the speed of motor 10 will be further accelerated.

Finally after another predetermined interval of time, the condenser discharge current decays to the value at which armature 18_a is set to drop out. Armature 18_a in dropping out, closes contacts 18_b to short circuit section 14_c of the resistor. 10 Motor 10 is accelerated to full speed. In the dropped out position of armature 18_a, interlock contacts 26 are closed to short circuit resistor 28.

The motor continues to operate at full speed 15 until the stop button 23 is depressed to deenergize the operating coil of contactor 22. As a result of deenergization, contactor 22 opens its normally open contacts 22_c to disconnect motor 10 from the source, and also opens its normally open contacts 22_a and closes its normally closed contacts 22_b 20 to leave the device in a reset condition for the next starting operation.

In the modification of the invention illustrated in Fig. 2, the operating coil which links the magnetic structures of the contactors is divided into 25 two portions comprising a portion 35 having a large number of turns, and a portion 35_a having a much smaller number of turns. In a typical example the portion 35 would have 25,000 turns 30 of four mil wire with a total resistance of approximately 17,000 ohms, and the portion 35_a would have 2,000 of eight mil wire with a total resistance of 180 ohms. These two winding portions correspond to the operating coil 19 of 35 Fig. 1.

The capacitor 36 which corresponds to the capacitor 20 of Fig. 1 is connected in parallel with only the high turn, high resistance portion 35 of the operating winding. No resistor corresponding to the resistor 28 is connected in series with the capacitor 36. An interlock 37 which corresponds to the interlock 26 of Fig. 1 is provided with normally closed contacts which normally short circuit the capacitor 36 and the high resistance portion 35 of the operating winding. The remainder of the modification of Fig. 2 is identical with the structure of Fig. 1.

The operation is as follows: Closing the "start" switch 38 connects the low turn portion 35_a of the operating coil across the source 39, 40. The circuit is traced from the side 39 of the source through "stop" switch 41, "start" switch 42 interlock 43 (corresponding to interlock 22_b of Fig. 1), normally closed interlock contacts 37, low turn portion 35_a of coil to side 40 of the source. In response to energization of portion 35_a of the coil, the armatures of the magnetic structures corresponding to armatures 16_a, 17_a, and 18_a of Fig. 1 are picked up and resistor sections corresponding to 45 14_a, 14_b, and 14_c are inserted in the armature circuit of the motor. Thereafter, the interlock corresponding to interlock 29_a, 29_b, 29_c of Fig. 1 is closed and as a result the line switch corresponding to switch 22 of Fig. 1 is closed to connect the motor to the line.

The closing of the armature corresponding to armature 18_a of Fig. 1 opens interlock 37 to interrupt the short circuit of capacitor 36 and of portion 35 of the operating coil. When the contacts 37 open, the capacitor 36 is quickly charged. However, in filling the capacitor current flows for a small fraction of a second of sufficient amount, through the low turn portion 35_a of the coil to insure that the armatures are completely closed 55 against their cores.

The closing of the line switch corresponding to line switch 22 of Fig. 1 opens contact 43 thereby disconnecting capacitor 36 and operating coil 35, 35a, from the side 11 of the supply source. Thereupon the capacitor 36 begins to discharge through the high resistance portion 35 of the operating coil, and as the discharge current decays, the contactor armatures controlled by the coil drop out in sequence and effect the short circuiting of the resistor sections in the motor armature circuit and the acceleration of the motor in the manner described in the explanation of the operation of Fig. 1.

Although in accordance with the provisions of the patent statutes this invention is described in concrete form and the principle thereof has been described together with the best mode in which it is now contemplated applying that principle, it will be understood that the elements and connections illustrated are merely illustrative and that the invention is not limited thereto, since alterations and modifications will readily suggest themselves to persons skilled in the art without departing from the true spirit of the invention or from the scope of the annexed claims.

What I claim as new and desire to secure by Letters Patent of the United States, is:

1. A motor starter comprising in combination, a current limiting device connected in the armature circuit of the motor, means for rendering portions of said current limiting device ineffective comprising an electromagnetic switching means having a plurality of independent magnetic circuits separately adjusted for actuation in response to different values of magnetic flux, a single operating coil linking all of said magnetic circuits and serving to energize all of said circuits, and electrical energy storage means connected to discharge into said coil so that the decay of current in said coil will cause said magnetic circuits to respond after predetermined time intervals to render said portions of said current limiting device successively inactive.

2. A motor starter comprising in combination, a current limiting device connected in circuit with the motor, a plurality of pairs of normally closed contacts for short circuiting portions of said current limiting device, means for actuating said contacts comprising a plurality of core structures which are magnetically independent of each other, a single operating coil linking said core structures and serving to excite magnetic flux in each of said core structures, a control device for energizing said coil and causing said core structures to open said contacts and insert said current limiting device in circuit with said motor, means responsive to said operation of said control device for deenergizing said coil, an electrical energy storage device connected to said coil and arranged to be connected to a source to provide for the storage of electrical energy therein and to be disconnected from said source in response to said operation of said control device so that it discharges a decaying current through said coil, said core structures being adjusted to close said pairs of contacts at different values of exciting flux so that said portions of said current limiting device are successively short circuited after predetermined time intervals.

3. A motor starter comprising in combination, a current limiting resistor connected in the armature circuit of the motor, a plurality of normally closed electromagnetic contactors for controlling portions of said resistor, the core structures of said contactors being separated so that

they are magnetically independent of each other, and each having drop out adjustment means whereby said contactors are adjusted to drop out at different values of flux, a single operating coil linking all of said core structures, a control device for exciting said coil to open said contactors and inserting said resistor in the motor circuit, an electrical energy storage device having connections to a source so as to have energy stored therein and having connections to said coil, means responsive to said opening operation of said contactors for completing the circuit of said motor to a source of supply and means responsive to said closing operation of said contactors for disconnecting said coil and said energy storage device from said source thereby to cause said energy storage device to discharge a decaying current through said coil to provide sequential dropping out of said contactors and short circuiting of said portions of said resistor.

4. A motor starter comprising in combination, a current limiting resistor connected in the motor armature circuit, a plurality of electromagnetic contactors having normally closed contacts for short circuiting portions of said resistor, the core structure of said contactors being separated so that they are magnetically independent of each other and each having drop out adjustment means whereby said contactors are adjusted to drop out at different values of flux, a single operating coil linking all of said core structures, a condenser connected to said coil and also having connections to a supply source, a control device for connecting said condenser to a supply source and for connecting said coil to a supply source to excite said cores and open said contacts to insert said resistor in said armature circuit, and a control contactor responsive to said opening operation of said resistor controlling contactors for connecting said motor to a supply source and for disconnecting said coil and said condenser from their source of supply so that said condenser discharges a decaying current through said coil to provide for sequential drop out of said contactors to effect sequential short circuiting of said portions of said resistor.

5. A motor starter comprising in combination, a current limiting device connected in the armature circuit of the motor, means for rendering portions of said current limiting device ineffective comprising an electromagnetic switching means having a plurality of independent magnetic circuits separately adjusted for actuation in response to different values of magnetic flux, an operating coil linking all of said magnetic circuits, said coil comprising a high resistance portion having a relatively large number of turns and a low resistance portion having a relatively small number of turns, and electrical energy storage means connected to said high resistance portion of said coil to discharge through said high resistance portion of said coil so that the decay of current in said portion will cause said magnetic circuits to respond after predetermined time intervals to render said portions of said current limiting device inactive.

6. A motor starter comprising in combination, a current limiting device connected in the armature circuit of said motor, a plurality of pairs of contacts for short circuiting portions of said current limiting device, means for actuating said contacts comprising a plurality of magnetic core structures which are magnetically independent of each other, a single operating coil linking said core structures, said coil comprising a high re-

sistance portion having a relatively large number of turns and a low resistance portion having a relatively small number of turns, a control device and means responsive to an operation of said control device for energizing said low resistance portion to control said contacts to insert said current limiting device in circuit with said motor, and a capacitor connected to said high resistance portion of said coil, means responsive to said operation of said control device for deenergizing

said low turn low resistance portion of said coil and causing said capacitor to discharge a decaying current through said high resistance portion of said coil, said core structures being adjusted to close said pairs of contacts at different values of magnetic flux so that said portions of said current limiting device are successively short circuited after predetermined time intervals. 5

FRED H. WINTER. 10

CERTIFICATE OF CORRECTION.

Patent No. 2,223,278.

November 26, 1940.

FRED H. WINTER.

It is hereby certified that error appears in the printed specification of the above numbered patent requiring correction as follows: Page 2, first column, line 54, strike out the comma after "circuit" and insert instead a period; and second column, line 31, for the reference numeral "35c" read --35a--; line 32, after "2,000" insert the word --turns--; page 3, first column, line 21, for "thereo" read --thereto--; line 58-59, claim 2, for "electrcal" read --electrical--; and second column, line 26, claim 4, for "structure" read --structures--; and that the said Letters Patent should be read with this correction therein that the same may conform to the record of the case in the Patent Office.

Signed and sealed this 14th day of January, A. D. 1941.

Henry Van Arsdale,
Acting Commissioner of Patents.
